CLAIM

The ornamental design for a computer unit, as shown and described.

DESCRIPTION

1.1 is a front view of a computer unit showing the new design;

1.2 is a back view thereof;

1.3 is a left side view thereof;

1.4 is a right side view thereof;

1.5 is a top view thereof;

1.6 is a bottom view thereof;

1.7 is a perspective view thereof;

1.8 is a back perspective view of Reproduction **1.1**, showing an alternative state of use with the rear support structure unfolded;

1.9 is a right side view thereof; and

1.10 is a front, left side perspective view of Reproduction **1.8**, showing the design in another state, with the tablet computer rotated 90 degrees.

The broken lines shown in the drawings illustrate portions of the computer unit that form no part of the claimed design.
